SORTING MACHINE FOR STATISTICAL RECORDS

Arthur H. Dickinson, Scarsdale, N. Y., assignor to International Business Machines Corporation, New York, N. Y., a corporation of New York

Application July 25, 1939, Serial No. 286,447

8 Claims. (Cl. 209—111)

This invention relates to sorting machines and more particularly to improvements in record controlled sorting machines adapted for sorting the individual records in accordance with the statistical data disposed thereon in the form of suitable index marks.

Heretofore, it has been customary to employ differently positioned index marks in different columns on the record elements or mediums for controlling the operations of statistical systems and having all the index marks in the different columns formed in precisely the same manner. For example, in the Hollerith system differentially positioned perforations are employed to represent the data, the size of which are all the same in the different columns on the record cards. In other suggested systems employing graphical characters on the record mediums in combination with different forms of analyzing devices the configurations of the index marks vary but solely for the purpose of identifying the value of the data representing marks.

In none of the systems suggested have index marks of different patterns or variations been used for determining the value of the representing mark by virtue of its differential position and in addition thereto by virtue of its configuration or pattern denote its columnar value or relationship with respect to the record medium. In most of the systems referred to, wherein the different columns or orders of data are sensed concurrently, columnar segregation or differentiation is obtained by the use of individual circuits or control elements, one for each column or order of data to be sensed, which in turn control the connected control means representing and controlling the individual and different orders of the data accumulating or printing sections of the machine.

It is now suggested that in the electrically controlled statistical systems, wherein different columns of data are sensed or analyzed concurrently for control purposes, a single control channel between the data sensing and data manifesting sections be employed instead of the multiple channels or conductors used at the present time. In addition thereto it is suggested to provide in the simplified and improved statistical system a novel combination of elements comprising in part data sensing means for analyzing concurrently the differentially positioned index marks on the records to initiate during the analyzing or sensing cycle differentially timed electrical impulses of different frequencies, a different frequency for each column of data sensed,

which are impressed upon the common circuit or channel connecting the said data sensing and manifesting sections. In this manner columnar segregation or differentiation of the data is obtained.

It is important to note that provision is made whereby the data sensing means is controlled directly by the index marks for creating the differentially timed electrical impulses. Light sensitive devices are provided for sensing the index marks on the records, which devices vary the electrical pulses or currents in the associated circuits in response to and in accordance with varying amounts of light to which the light sensitive devices are subjected. Novel records are provided for controlling the light sensitive devices not only at differential times in the sensing cycle when the index marks thereon are sensed, but also for controlling the different light variations to which the said devices are subjected at the particular timed intervals the index marks are sensed in the cycle. The index marks of the novel records are differentially positioned thereon in different columns to represent the different values of the data represented thereby. The configurations or patterns of the index marks in each column are alike, but the patterns of the index marks in the different columns differ with respect to each other. These index marks comprise light controlling representations which are formed in different patterns having a plurality of light controlling portions arbitrarily disposed in the index mark areas for controlling the frequencies of light variations directed to the associated light sensitive devices, or stated in other words, the light controlling portions are arranged in the index mark areas for controlling the changes in the amounts of light to which the associated light sensitive devices are subjected. It is now understood that upon sensing these index marks having different light controlling properties the light sensitive devices are controlled accordingly to generate electrical oscillations differing in frequency depending upon the frequencies of light interruptions caused by the index marks. The differentially timed impulses or oscillations of different frequencies which are generated are then impressed upon the common connecting circuit for controlling the data manifesting sections. Appropriate tuned circuits are provided with the different control elements for each order of the data manifesting sections to direct the impulses of different frequencies to the proper control elements thereby controlling the

statistical operations of the machine in accordance with the sensed index marks.

- Provision must be made in the suggested system just described for sorting or segregating the records referred to, which records are provided with differentially positioned index marks of varying patterns. The subject matter of the instant application pertains solely to the sorting means adapted to be controlled by such records.
- 10 In this application, the control circuits referred to hereinabove are utilized for controlling the operations of the sorting means. The novel records referred to and described hereinbelow, and accounting machines having automatic control features for controlling the feeding of the records and the selective accumulation of the recorded data, are claimed in copending applications filed July 25, 1939, Serial Nos. 286,444, 286,448, and 286,449, respectively.
- 20 Means are provided whereby the sorting control magnet is not only energized at the differential times the index marks are sensed, but energized at such times only if the frequencies of the oscillations initiated by the sensed marks correspond to selected or predetermined frequencies desired to be sorted.

Accordingly, an object of the present invention resides in the provision of means for segregating records in accordance with the differentially positioned index marks on the records and/or in accordance with the frequency values represented by the index marks.

Other objects of the invention will be pointed out in the following description and claims and illustrated in the accompanying drawings, which disclose, by way of example, the principle of the invention and the best mode, which has been contemplated, of applying that principle.

In the drawings:

- 40 Fig. 1 is a detail view of a fragmentary section of a novel record card.
- Fig. 2 is a diagrammatic view of one form of record analyzer.
- Fig. 3 is a detail of a light limiting disk.
- 45 Fig. 4 is a section of the sorting machine showing the major control elements thereof.
- Fig. 5 is a circuit diagram of the machine.
- Fig. 6 is a timing diagram of the machine.

Control records

- 50 Referring now to Fig. 1 one of the preferred types of light controlling records adapted for use in the novel statistical machine will be described. The reference numeral 10 designates 55 a record card similar to the type now used in the present Hollerith statistical system which is shown divided into different columns as indicated at a, b, c, etc. Each column is divided into twelve index point or mark positions, so that the 60 positioning of the index marks at these different positions in the different columns denotes the different values of the data represented by the index marks. The differently positioned index marks are shown in the said figure and indicated 65 by the reference numeral 11. It is to be noted that the configurations of the index marks in the different columns which in Fig. 1 comprise graphical wave forms or patterns are different with respect to each other. It is to be understood 70 that the configurations of the index marks appearing in each column, but at different positions therein, are alike. It is seen that the light and dark portions of the index mark areas are arbitrarily arranged so as to produce differently 75 shaped wave forms or patterns. The purpose

of the described arrangement is for controlling the changes in the amount of light directed to cooperating light sensing devices whenever the index marks are scanned or sensed by the rays of light. The method of analyzing or sensing the index marks will be described presently. The record card 10 is opaque, therefore reflected light is directed to the light sensitive devices whenever the card and index marks thereon are exposed to the light rays. It is well known that varying amounts of light are reflected by light and dark areas on control records which are scanned by light rays, the frequency of the light variations depending upon the arrangement of the light controlling portions or areas. It is seen 10 that the configurations of the graphical patterns at the different index mark positions in the columns differ with respect to each other, and for illustrative purposes, assume that the configurations are so shaped so that the index 20 mark 11 in the column designated a is effective to cause f1 variations in the light reflected thereby, or stated in other words represents a frequency of f1, the index mark in column b represents frequency f2, the index mark in column c 25 represents frequency f3, etc. It will be understood as the description progresses that the different frequencies represented by the different index marks will be effective for determining the columnar segregation or differentiation of 30 the data represented by the index marks. The varying patterns of the index marks may be printed in black ink on record cards affording a white background for the marks, or if desired the light controlling records may be made photographically in accordance with well known photographic methods. The record cards can be provided with a light sensitive surface so that individual light controlling patterns or graphs can be formed thereon photographically. 40

Analyzing the light controlling records

Referring now to Figs. 2, 3, and 4 the method of and means for analyzing or sensing the light controlling index marks disposed on the records 45 will be described.

A lens system is provided comprising two lenses 16 and 17 to cause a narrow beam of light to be projected on the record card 10 from the light source 18. A lens system comprising lenses 19 50 and 20 is provided to focus the light reflected from the record upon a light sensitive device 21. Interposed between the individual lenses 19 and 20 a slotted disk 22 is provided to limit the amount of light reflected 55 and projected from the card to the photocell. It is understood now, that, if a record card provided with differently shaped patterns at different index mark positions is fed past the sensing station described, the amount of light reflected 60 and transmitted to the photocell will pulsate or vary exactly in accordance with the pattern of light and dark portions of the index mark sensed. If the photocell is connected in a closed circuit, the varying amounts of light projected thereon 65 will cause a corresponding pulsating current to flow therein, the frequency of which will correspond to the frequency of the variations in the light caused by the sensed index mark. It is obvious that the varying amounts of light are 70 directed to the photocell only at the particular timed intervals the index marks are fed past the said beam of light. The position where the said beam of light is projected upon the card will be referred to as the data sensing position. 75

In Fig. 4 the reference character 25 designates an assembly comprising the lens 16 and 17 and a suitable housing or case which assembly is fixed in the insulating block 26. Similarly, the lens 19 and 20, and disk 22 with a suitable housing are designated 27 which assembly also is fixed in the said block. The light source 18 is disposed within block 26 directly above the first mentioned lens system and inserted in a suitable socket 28 provided with conducting rods 29 which engage and slide along the conducting rails 30 whenever the block 26 is positioned from one columnar position to another. The said conducting rails are secured to a suitable insulating member 31 which in turn is fastened to the frame of the machine. A second pair of conducting rods is provided to afford a connection to the photocell 24 which receives the light reflected from the record by means of the lens 19 and 20 and a light conducting member such as the quartz rod 33. The insulating block 26 or carriage is slidably supported by the square bar 34 which extends across the machine and can be fastened to the side frames thereof. Also, journaled in the side frames is the worm shaft 35 which engages the partial nut 36 secured in the block 26. By means of a suitable crank the worm shaft can be rotated to set the carriage to any desired columnar position for effecting the sensing of the index marks in the selected columnar positions.

Record sorting means

The mechanical features embodied in the present invention are predicated upon the principles described in U. S. Patents Nos. 1,982,216 and 1,933,357. For this reason the following brief description is deemed sufficient. Referring now to Figs. 4 and 5, the motor 50 which drives the sorting mechanism by gearing not shown is started by depressing a start key 51 to complete a circuit from conductor 52 to contacts 53 of the start key, relays R1, R2, and R3 to conductor 54 energizing the said relays. Closure of contacts R2a and R3a connect the motor terminals to the power supply conductor to start the motor. A holding circuit is then established from conductor 52 to contacts 65a (the usual card lever contacts), contacts 66 of the stop key, contacts R1a to relays R1 to R3 and conductor 54 thereby effecting continuous operation of the machine.

The records 10 are fed from the magazine by means of a picker 55 actuated by the slotted arm 56 which is oscillated once each machine cycle by a crank pin 58 on the disk 59 through the link 57, which link is pivoted to both the crank pin and the slotted arm. The disk 59 is fixed to a shaft 60 which is driven by any suitable means by means of the motor. A record removed by the picker mechanism from the magazine is brought between the first set of feed rolls and carried to the left far enough for similar feed rolls 13 and 14 to grip the record and advance it to the appropriate sorting pocket (one of which is shown at 61).

The sensing means described hereinabove is positioned between the pairs of feed rolls 12 and 13 to sense the differentially positioned index marks in the desired columns of the records. The guide blades 62 rest upon an armature 63 associated with the control magnet 64. The ends of the guide blades are so spaced relative to the sensing means so that the index marks on the records are sensed at the instances the left edges of the record underlies the end of the

guide blade corresponding to that index mark position. Each guide blade leads to a sorting pocket which is designed to accumulate all of the records having a given index mark in the column analyzed, providing the index mark is formed with a predetermined pattern or waveform. The usual provision is to provide a sorting pocket for each index mark position on the record and an additional reject pocket. The first blade on the right corresponds to the "9" 10 pocket, the next to the "8" pocket, etc.

In view of the description hereinabove, it is understood now that as the differently shaped index marks are fed past the sensing position photocell 24 is subjected to light variations in accordance with the patterns of the index marks at the differential times the said index marks appear at the sensing position. Now, whenever the photocell 24, which is connected to the input of the amplifier unit generally designated 65 20 is subjected to such light variations, the said cell is effective to control the conductivity of the amplifier so that electrical oscillations of frequencies corresponding to the frequencies of the light variations impressed upon the cell are 25 caused to flow in the output circuit of the amplifier which includes the primary winding of the transformer 66. To each of the secondary windings of the said transformer suitable filtering and rectifying units are connected which are 30 represented generally by the reference characters 67 and 68, respectively. Each of the filters 67 are so adjusted that only one frequency of the multifrequency oscillations is passed by each filter which in turn is impressed upon the connected rectifying and the common amplifying unit 69 to effect energization of the control relay 70 which is included in the output of the amplifier unit.

Now, assume that the sensing means is properly positioned for sensing a desired columnar position on the records and that the index marks on some of the records in the selected column are formed to represent frequency f_1 , that some index marks in the same column on other records are formed to represent frequencies f_2 and f_3 . Furthermore, assume that it is desired to segregate only those records which have the index marks formed to represent frequencies f_1 and f_3 . For these conditions the filter units 45 are tuned for frequencies f_1 and f_3 are connected to the secondary windings of the transformer 66. Now, as the oscillations of frequencies f_1 and f_3 are initiated by the sensed index marks these 50 oscillations are passed by the said filters to be impressed upon the related rectifying units and thence upon the common amplifier unit to energize relay R4 at the particular timed intervals the index marks are sensed. All other index 55 marks initiating oscillations of different frequencies are blocked by the filter units and present these oscillations to effect energization of relay R4. Upon energization of the said relay contacts R4a are closed, and a circuit is completed to the sorting control magnet 64 when the contacts R4a are closed at a timed interval when the column selector 70 is effective to be conductive. It is well known in the art that the column selector 70 can be set to represent any desired index mark position and is effective to complete the circuit connected thereto only at a timed interval representative of the selected index mark position. Now, whenever the index 60 marks sensed initiate oscillations of the selected frequencies and at the timed intervals for repre-

65 70 75

senting the index mark position for which the column selector is set a circuit is completed from conductor 52 to the impulse distributor 71, column selector 70, contacts R4a, relay R5, and sorting magnet 64 to conductor 54 energizing the said relay and magnet.

A holding circuit is then established through the conducting ring C1, contacts R5a, relay R5 and magnet 64 to conductor 54 which is maintained energized until near the end of the machine cycle (see timing chart). Energization of the sorting magnet then effects positioning of the armature and the sorting blades to direct the desired cards to the appropriate sorting pockets.

While there has been shown and described and pointed out the fundamental novel features of the invention as applied to a single modification it will be understood that various omissions and 20 substitutions and changes in the form and details of the device illustrated and in its operation may be made by those skilled in the art without departing from the spirit of the invention. It is the intention, therefore, to be limited only 25 as indicated by the scope of the following claims.

What is claimed is:

1. In a sorting machine of the character described controlled by records bearing differentially positioned index marks, the relative positioning thereof representing the different values of the data, said index marks being formed to represent different frequency values in accordance with their formations, a sensing station, means for feeding the records past the sensing 30 station at a constant speed, means for sensing the index mark positions on each record for determining the different positions of the index marks on the records including means for determining the frequency values represented by the sensed index marks, and sorting means comprising means controlled by the sensing means, at differential times, for sorting the records in accordance with the positions of the index marks on the records including means for rendering 40 the said controlled means effective only when the sensed index marks are formed to represent predetermined frequency values.

2. In a sorting machine of the character described controlled by records bearing differentially positioned index marks, the relative positioning thereof representing the different values of the data, said index marks being formed to represent different frequency values in accordance with their formations, a sensing station, 50 means for feeding the records past the sensing station at a constant speed, means for sensing the index mark positions on each record for determining the different values of the differentially positioned index marks on the records including means for determining the frequency values represented by the sensed index marks, and means controlled by the sensing means, at differential times, for selecting the records selectively in accordance with the values of the sensed index marks including means for effecting the selecting operations selectively in accordance with the frequency values represented by the sensed index marks.

3. In a sorting machine of the character described controlled by records bearing differentially positioned index marks, having different light controlling properties, the relative positioning thereof representing the different values of the data, a sensing station, means for feeding the records past the sensing station at a con-

stant speed, means for sensing the index mark positions on each record for determining the different positions of the marks on the records comprising a light source and light responsive means, the latter being conditioned by the rays of light directed thereto, which light rays are modified by the light controlling properties of the index marks, means controlled by the sensing means for generating oscillations of different frequencies in accordance with the conditioning of the light responsive means at the different timed intervals the index marks are sensed, and means controlled by the oscillations generated at the differential times for selecting the records selectively in accordance with the values of the index marks including means controlled by the oscillations for effecting the selecting operations selectively in accordance with the frequencies of the oscillations initiated by the sensed index marks.

4. In a sorting machine of the character described controlled by records bearing differentially positioned index marks formed to represent different frequency values in accordance with their formations, the relative positioning thereof representing the different values of the data, a sensing station, means for feeding the records past the sensing station at a constant speed, means for sensing at different timed intervals the different positions of the index marks, means controlled by the sensing means for generating oscillations of different frequencies in accordance with the formations of the index marks at the timed intervals the index marks are sensed, and means controlled by the oscillations generated at the differential times for selecting the records selectively in accordance with the values of the index marks including means for effecting the selecting operations selectively in accordance with the oscillations initiated by the sensed index marks.

5. In a statistical machine controlled by records bearing differentially positioned index marks, the relative positioning thereof representing the different values of the data, said index marks being formed to represent different frequency values in accordance with their formations, a sensing station, means for feeding the records past the sensing station at a constant speed, means for sensing the index mark positions on each record for determining the different positions of the index marks on the records including means for determining the frequency values represented by the sensed index marks, and means controlled by the sensing means for controlling the machine operations and operated at differential times in accordance with the values of the sensed index marks including means for rendering the said controlled means effective only when the sensed index marks are formed to represent predetermined frequency values.

6. In a statistical machine controlled by records bearing differentially positioned index marks, the relative positioning thereof representing the different values of the data, said index marks being formed to represent different frequency values in accordance with their formations, a sensing station, means for feeding the records past the sensing station at a constant speed, means for sensing the index mark positions on each record for determining the different positions of the index marks on the records including means for generating oscillations of different frequencies in accordance with the formations of the sensed index marks, means for segre-

gating the generated oscillations of different frequency values, and means conjointly controlled by the sensing and segregating means for controlling the machine operations and operated at differential times in accordance with the positions and frequency values of the index marks on the records.

7. In a statistical machine controlled by records bearing differentially positioned index marks, the relative positioning thereof representing the different data values, said index marks being formed to represent different frequency values in accordance with their formations, a sensing station, means for feeding the records past the sensing station at a constant speed, means for sensing the index mark positions on each record for determining the different data values of the index marks on the records including means for determining the frequency values represented by the sensed index marks, and means controlled selectively by the sensing means for controlling the machine operations at differential times in accordance with the data values of the sensed index marks including means for rendering the said controlled means effective selectively in accordance with the frequency values of the sensed index marks.

8. In a statistical machine controlled by rec-

ords bearing differentially positioned index marks, having different light controlling properties, the relative positioning thereof representing the different values of the data, a sensing station, means for feeding the records past the sensing station at a constant speed, means for sensing the index mark positions on each record for determining the different positions of the marks on the records comprising a light source and light responsive means, said light responsive means being conditioned by the rays of light directed thereto, which rays are modified by the light controlling properties of the index marks, means controlled by the sensing means for generating oscillations of different frequencies in accordance with the conditioning of the light responsive means at the different times the index marks are sensed, and means selectively controlled by the oscillations generated at the differential times, in accordance with the values of the index marks for controlling the machine operations including means controlled by the oscillations for rendering the controlled means effective selectively in accordance with the frequency values of the oscillations initiated by the sensed index marks.

ARTHUR H. DICKINSON.
